UNITED STATES PATENT OFFICE.

STEWART B. PALMER, OF SYRACUSE, NEW YORK.

IMPROVEMENT IN LOW-WATER ALARMS FOR STEAM-GENERATORS.

Specification forming part of Letters Patent No. 82,025, dated September 8, 1868.

To all whom it may concern:

Be it known that I, STEWART B. PALMER, of Syracuse, in the county of Onondaga and State of New York, have invented a new and useful Improvement in Low-Water Alarms for Steam Generators; and I do hereby declare that the following is a full, clear, and exact description of the same, reference being had to the annexed drawings, making part of this specification, in which—

Figure 1 is a perspective view of the completed instrument as applied to a steam-generator; and Fig. 2 is a perspective view, showing the lower chamber, the whistle, and the means for conducting the steam from the chamber to said whistle.

Similar letters denote corresponding parts in both figures.

This invention relates to that class of low-water alarms in which the expansion of metallic tubes is made to operate upon the valve of an alarm-whistle, by which means notice of the low-water level which has obtained within the boiler is given to the person in attendance; and it consists in the combination of metal tubes closed at their upper or outer ends by being surmounted with an air-chamber, and a chamber to which the lower or inner ends of such tubes are attached, and through which they are supplied with steam from the generator, with rods running from the lower chamber to and connecting with the air-chambers on the outer ends of the tubes, and with levers, also connected to the air-chambers, and to a rod leading to the disengaging mechanism of the whistle-valve, said rod being included in the combination; and it further consists in the arrangement of a whistle and its valve-disengaging mechanism, with reference to the chamber from which it receives steam.

In the annexed drawings, A is a tube or pipe by which the device is, or may be, connected to the generator, and which extends downward therein, terminating at the low-water line, so that as the water reaches that point steam will enter the pipe and pass through the chamber B into the tubes C, causing them to expand sufficiently to operate upon the valve-disengaging device, by which means the alarm is sounded.

B is the lower or inner chamber, to which

the pipe A and tubes C C are attached. This chamber is triangular in its cross-section, the space within it being of the same configuration for the purpose of conducting steam to the tubes C.

C C are tubes extending upward or outward from the chamber B to any desired extent which may be necessary to give them the requisite flexibility, their outer ends being closed by their being surmounted by air-chambers D D, in the form of spheres, or of any other suitable shape. These tubes are firmly attached to the chamber B, and the space within them communicates with the steam-space within said chamber, so that as the water within the generator falls below the mouth of the pipe A, steam will enter said pipe and pass up to the chamber B, and thence into the tubes C C, thus increasing the temperature of said tubes, which, in consequence of their being held in position by the rods F F, and of their increased length caused by such increased temperature, will assume the position shown by dotted lines in Fig. 1. As a consequence of the above-described change of position of the tubes, the links a a will have their lower ends carried farther apart, which action will depress their upper ends, thus carrying down with them the rod H, which rests upon and opens the whistle-valve.

E is a plate of metal secured to the back side of the chamber B, and extending up in an inclined position until its upper end is nearly in a line with the tubes C C, its extreme upper end being slotted so as to receive and form a guide for the rod H, which bears upon the whistle-valve. At a suitable distance above the whistle a lever, I, is pivoted to the plate E, and projects forward some distance and rests upon the stem of the whistle J. Upon the upper side of this lever, and immediately above the whistle, rests the rod H. The arrangement of these parts is such that when, by the increased length of the rods C C, consequent upon their expansion, they depress the upper ends of the levers a a, it carries down the rod H and lever I, which act immediately upon and open the whistle-valve.

To provide against the necessity of leaving the whistle-valve open, and consequently, the whistle sounding until the water has been supplied to the generator in sufficient quantity to

cover the mouth of the pipe A, provision is made for closing said valve at once by providing an offset or notch in the upper side of the lever I, so that as the rod H is driven forward by means of a cord attached to a ring formed upon said rod, it (the rod) is removed from its bearing upon the lever I, and the said lever and whistle-valve are allowed to rise, thus shutting off the steam.

F F are the rods above referred to, which are at their lower ends secured to ears or projections upon the lower edge of the chamber B, said rods carrying upon their extreme lower ends, and beneath the ears, nuts G G, for the purpose of lengthening or shortening said rods.

J is the whistle, which is secured to the upper side of the chamber B, and is constructed in the form of a tube, having a sliding plate arranged upon its front face for adjusting the pressure within said whistle, and for removing any sediment that may collect therein.

K is the pipe through which dry steam may be conducted to the whistle from any convenient place, or, saturated, may be supplied from the chamber in the base B.

a a are the links which are connected to the

chambers D D and to the rod H, the functions of which have heretofore been explained.

b is a spiral spring, which is attached to the rod H and to the plate E, in such a manner that when all the parts are in proper position, as shown in Fig. 1, the weight of the rod H and links a a will be secured upon and supported by said spring, thus relieving the whistle-valve from such weight.

What I claim as my invention, and desire to secure by Letters Patent, is—

1. The combination of the chamber B, tubes C C, with their surmounting chambers D D, rods E E, links a a, and rod H, arranged and operating substantially as shown and described.

2. The arrangement of the rod H, lever I, and spring b, with reference to the whistle J, and its valve.

In testimony whereof I have signed my name to this specification in the presence of two subscribing witnesses.

STEWART B. PALMER.
